UNITED STATES PATENT OFFICE

WALTER RALEIGH DARNELL, OF LONG BEACH, CALIFORNIA

DESK LEG GLIDE SHOE

Application filed September 16, 1929. Serial No. 392,988.

The object of this invention is to provide an improved construction for a glide shoe for legs of furniture such as desks and the like.

5 A further object is to provide an improved glide shoe which has a smooth bottom surface to facilitate sliding on a floor or floor covering and which has smoothly rounded corners and edges to prevent injury to other 10 objects.

Still another object is to provide an improved glide shoe having its lower portion drawn out of a sheet of metal and its upper portion formed by pressing the metal, the 15 upper portion being provided with slits at the corners of the shoe to allow for slight variations of dimension in the leg or ferrule on which the shoe is to be mounted.

Another object of the invention is to provide 20 a glide shoe arranged to frictionally engage an object, the shoe being of smaller inside dimension at its top than at its bottom so that when in place it will fit snugly and will not easily drop off.

25 Another and further object is to provide a glide shoe so designed as to prevent the accumulation of dirt and moisture on account of having a particularly close fit at its top to the object on which it is mounted.

30 A further object is to provide a glide shoe which can be easily removed and replaced.

With these and other objects in view, my 35 invention consists in the construction, arrangement and combination of elements hereinafter set forth, pointed out in my claims and illustrated by the accompanying drawings, in which:

Figure 1 is a perspective view of a portion of a desk equipped with my improved 40 glide shoe.

Figure 2 is an enlarged perspective view of one form of glide shoe.

Figure 3 is a side elevation of a portion of a desk leg ferrule, one of the glide shoes being 45 shown, in section, in position for mounting thereon.

Figure 4 is a sectional view showing a shoe in place on a desk leg ferrule.

Figure 5 is a plan view of the form of shoe 50 shown in Figure 2.

Figure 6 is a perspective view of a slightly modified form of the glide shoe.

Figure 7 is a sectional view showing the modified form of shoe in position for use on a desk leg.

This glide shoe is especially designed for use on an article of furniture such as a desk 10 having legs 12 which in this instance are square in cross-section. The legs 12 usually are provided with metal ferrules 14 at their lower ends, which sometimes are formed somewhat tapering.

The shoe according to the showing in Figures 1 to 5 inclusive is formed from a sheet of 15 suitable metal such as brass, preferably similar to the ferrules of the desk legs on which the shoes are to be used.

The metal is pressed and partially drawn to form the shoe, which has a bottom 16 and four side walls 18.

Because of this method of formation, the 20 shoe is integrally formed and the four walls 18 thereof are continuous and without breaks in their lower portions. The upper portions of adjacent walls, however, are separated by 25 slots or notches 20 extending part way down from the top at the respective corners of the shoe.

The walls 18 are pressed so as to slope inwardly somewhat at their upper margins, as 30 clearly shown in Figures 3 and 5. In other words, the shoe has a less inside dimension at its top than at its bottom. This causes the slots or notches 20 to be open to greater 35 extent at their lower than at their upper ends, as indicated particularly in Figure 2.

By this arrangement a resilient wall construction is provided and the upper portions of the walls 18 are permitted to spring outwardly under pressure, by a further opening of the upper ends of the slots or notches 20.

The tapered lower end of the ferrule 14 is smaller than the normal dimension of the upper end of the shoe to be used thereon.

The shoe can be placed beneath the leg, as indicated in Figure 3, with the lower end of the ferrule resting on the upper end of the shoe. Then pressure is applied upwardly on the shoe, or downwardly on the desk, to cause the shoe to be forced into place on 100

the ferrule, the walls 18 springing out somewhat along the surfaces of the ferrule.

This gives a very easy and convenient method of mounting the shoe, which is held 5 in position solely by the frictional contact of its walls with the object such as leg ferrule.

The lower surface of the bottom 16 is smooth, and it may be slightly convex if desired. This provides an easy sliding contact with a floor or floor covering.

10 It will be noted from Figures 3 and 4 that the corners between the bottom 16 and walls 18 are nicely rounded, and from Figure 5 that the lower unslotted portions of the corners between adjacent walls 18 are also rounded. This prevents injury to the floor or to other objects which may be contacted by the shoe.

15 The tight frictional fit of the upper edges 20 of the walls of the shoe insures that the device will be held in place, and also prevents the entrance of dirt, water or other substances.

25 The corner openings 20 help to provide the required resilience and also serve to compensate for some variation in the dimensions of the ferrules or furniture legs with which the shoe may be used.

30 According to the form shown in Figures 6 and 7, the bottom member 16' of the shoe is of considerably greater area than the space enclosed by the upper portions of the side walls 18'. The bottom 16' and walls 18' are connected by a bulging portion designated 35 by the numeral 22 which projects outwardly a material distance at the bottom of the shoe. In this construction the openings 20' at the corners of the shoe may be mere slits which extend downwardly a portion of the 40 distance from the upper margins at the respective corners between adjacent side walls.

45 The construction according to Figures 6 and 7 affords a larger bearing surface of the shoe on the floor and also affords a more attractive appearance.

50 It is to be understood that the shoe, of either form, may be any desired size and further, that the shoe may be made of any desired shape in plan to fit furniture legs of different sizes and shapes.

55 The shoe of either formation provides a very inexpensive, attractive, convenient, serviceable and durable glide attachment for legs of desks and the like.

55 I claim as my invention:

1. A glide shoe for use on an object, comprising a bottom and inwardly sloping walls adapted to frictionally engage and be held in contact with the walls of the object, adjacent walls of the shoe being separated in their upper portions by corner slots or notches which notches normally are of greater width at their lower than at their upper ends.

60 2. A glide shoe for furniture legs and the like, comprising a bottom and walls there-

on, said walls having their upper edges in engagement with the object substantially throughout the periphery thereof to prevent the entrance of dirt and moisture thereto, said walls sloping outwardly from their upper edges and being vertically slotted at intervals to facilitate outward springing of the walls in mounting the shoe on an object and to cause the upper edges to frictionally grip the sides of the object.

70 Des Moines, Iowa, August 24, 1929.
